CIRCUIT INTERRUPTER EMBODYING
POLYTETRAFLUOROETHYLENE

Albert P. Strom and Leo J. Berberich, Pittsburgh, Pa., assignors to Westinghouse Electric Corporation, East Pittsburgh, Pa., a corporation of Pennsylvania

Application March 20, 1947, Serial No. 736,070

6 Claims. (Cl. 200—149)

1

This invention relates to circuit interrupters, and more specifically to circuit interrupting devices embodying arc confining and extinguishing members prepared from polytetrafluoroethylene.

While a number of arc confining and extinguishing materials have been employed in circuit interrupters, certain prior art materials have been so outstanding in this service that they are often selected as a standard of comparison. In particular, horn or vulcanized fiber has exhibited such generally desirable characteristics over a wide range of conditions of use that it is commonly accepted as a standard of comparison for most materials. In certain applications, however, the heat of the arc being interrupted is so intense that even fiber erodes extensively, while other organic substances erode so much more that various undesirable features such as excessive carbonization, and excessive gas formation leading to back blast may occur. Therefore, the arc confining structures comprising horn fiber and other materials must be replaced at frequent intervals in order to maintain maximum efficiency in the breaker device.

It has been discovered that polytetrafluoroethylene has the unusual property of eroding to a markedly lesser extent than does horn fiber under the same conditions of use in the presence of electrical arcs. Tests have also indicated that polytetrafluoroethylene is exceptionally suitable for use as an arc confining and extinguishing material in any of a great variety of circuit interrupting devices.

The object of this invention is to provide a circuit interrupter with an arc confining and interrupting structure comprising polytetrafluoroethylene.

Other objects of the invention will in part be obvious and will in part appear hereinafter. For a better understanding of the nature and objects of the invention, reference should be had to the following description and drawings, in which:

Figure 1 is a fragmentary view in elevation partly in section of a magnetic type of circuit interrupter.

Fig. 2 is a fragmentary view in elevation partly broken of a compressed air type of circuit breaker.

Fig. 3 is a vertical cross-section of a portion of a restricted orifice gas blast circuit breaker.

Fig. 4 is a vertical cross-section through a fuse.

Fig. 5 is a graph plotting the relative erosion of polytetrafluoroethylene compared to fiber in a fuse up to 2000 amperes of current, while

2

Fig. 6 plots the relative erosion volumes of fiber and polytetrafluoroethylene up to 12,000 amperes in a gas blast breaker.

According to the present invention, arc confining and extinguishing portions of circuit interrupters are prepared from polytetrafluoroethylene. Polytetrafluoroethylene has been found to erode less than any known organic material when subjected to the heat of an electrical arc.

10 Polytetrafluoroethylene is composed of carbon and fluorine, and has the generic formula

15 When the polytetrafluoroethylene is subjected to high temperatures, as in an arc, the fluorine to carbon bond appears to be more stable than the carbon to carbon bond, and lower polymers result with very little free carbon being produced. The dielectric strength and other electrically insulating properties of polytetrafluoroethylene are outstanding.

20 For producing structures embodying polytetrafluoroethylene, they may be machined from solid blocks of the polymer by using conventional metal or wood working tools or else the structures may be molded from the powdered polymer and sintered under heat and pressure, as disclosed in the Patents 2,406,127; 2,400,099; 2,400,094 and 2,230,654. In order to impart increased strength for supporting loads when heated to temperatures above 300° C., the polytetrafluoroethylene may be combined with glass fibers either loose or in the form of a fabric by applying thereto powdered polytetrafluoroethylene or interleaving films of polytetrafluoroethylene with webs or sheets of glass fiber fabric and molding under heat and pressure into a homogeneous solid.

25 30 35 40

35 40 45 Members composed of polytetrafluoroethylene may be employed for arc splitters and for arcing chambers, fuse tubes, arc gaps, insulating supports adjacent the arc, and for other structures in arc interrupting devices. For securing best results, both mechanically and electrically, the polytetrafluoroethylene should comprise the major proportion of the member, particularly where the structure is intended to develop an arc-extinguishing gas. Less than 50% of the weight of the member may be composed of rein-

forcing fibers, such as asbestos or glass fibers, or solid inorganic materials, such as titanium dioxide, silica, magnesium oxide, or the like. It will be appreciated that other gas-evolving materials, such as boric acid, ammonium borate or magnesium borate, as well as reinforcing solids, may be incorporated in the polytetrafluoroethylene.

Referring to Figure 1 of the drawings, there is illustrated a magnetic circuit interrupter 10 embodying the features of the present invention. The circuit interrupter comprises a pair of arc-ing contacts 12 and 14 disposed within a casing comprising wall 16 which may be prepared from sheets or panels of polytetrafluoroethylene. A magnetic coil 18 adapted to be energized when the contacts 12 and 14 are separated is associated with a magnetic core 20 and magnetic field pole plates 22 for drawing an arc upwardly into an arc-extinguishing structure comprising a plurality of splitter plates 24 of polytetrafluoroethylene, or polytetrafluoroethylene reinforced with glass fibers or containing other fillers. The arc is transferred on the separation of the contacts 12 and 14 to the arcing horns 26 and 28 and under the influence of the magnetic field between the field pole 22, it will be drawn up into the arc-extinguishing splitter plate structure where the arc is attenuated and extinguished by the action of small but highly effective amounts of arc-extinguishing gases generated from the polytetrafluoroethylene plates 24.

Experience with splitter plates of a great many organic insulating solids indicated that they evolved such relatively great quantities of gas that arcs would be blown back out of the plate structure in magnetic circuit interrupters without being interrupted satisfactorily. Also these organic materials carbonized excessively and were rendered poor insulators so that the operation became progressively poorer. Therefore, ceramic splitter plates are used commercially almost exclusively in magnetic circuit interrupters. However, ceramic splitter plates have the disadvantage of low surface dielectric strength when heated by impinging electrical arcs and a large number of plates, with a bulky structure, are required for satisfactory operation. For example, a magnetic breaker capable of interrupting a maximum of 7500 volts 60 cycle current requires a minimum of 48 plates of porcelain embodied in a casing 18 inches wide.

A considerably smaller number of splitter plates of polytetrafluoroethylene, due to its unusual properties, can be employed in the magnetic circuit interrupter. The amount of gas evolved on arcing is small and does not cause gas blow back, but is sufficient to improve the function of the apparatus. A further advantage resides in the considerable reduction in size of the splitter structure with a smaller magnetic coil and field pole plate structure as compared to that required for a ceramic plate structure.

For an illustration of a gas blast circuit breaker embodying polytetrafluoroethylene, reference should be had to Fig. 2 of the drawings. The gas blast circuit breaker 30 comprises a stationary contact member 32 and a movable contact arm 34 adapted to create an arc when they are separated in the process of interrupting a circuit in which the contact members are embodied. The end of the contact 34 enters through a slot 36 in a throat 40 composed of polytetrafluoroethylene. A stream of compressed gas, such as air, is released into a conduit 38 at the time the con-

tact member 34 is being separated from contact 32 and the gas blast blows the arc produced against the splitters 42 composed of polytetrafluoroethylene. The splitters 42 evolve a small amount of an arc-extinguishing gas which does not generate a back blast and thereby enables the arc to be readily attenuated by being blown into the splitter structure. The low amount of gas generated from the polytetrafluoroethylene is readily blown away by the gas blast and the arc successfully extinguished when the current reaches zero.

In Fig. 3 of the drawings, there is illustrated a restricted orifice type of gas blast circuit breaker 50. In this breaker, the contact members 52 and 54 are separated from one another by an appropriate mechanism when it is desired to interrupt the circuit in which the interrupter is embodied. The contact members 52 and 54 are disposed in a tubular member 56 having a contracted diameter 58 resulting in a restricted orifice 60 where the contacts normally meet in closing the circuit. The orifice 58 and a reinforcing tube 62 may be both prepared from polytetrafluoroethylene, though for most purposes only the portion 58 bearing the restricted orifice need be made from polytetrafluoroethylene. The remaining structure may be prepared from materials possessing a suitable physical strength or other desired characteristics.

In interrupting a circuit, the contact members 52 and 54 being in closed position at constricted throat 60, the contact members 52 and 54 are separated and a blast of air or other gas is directed along the tubular member 56. The blast of air is intensified in speed at the constricted throat 60 so that its cooling action is increased. The heat of the arc causes arc-extinguishing gases to be evolved from the polytetrafluoroethylene throat structure 58 and this also assists in cooling the arc. At current zero, the lengthened and cooled arc is readily extinguished. Since the shape and size of the throat 60 are critical, the use of polytetrafluoroethylene is particularly beneficial in that so little of the material is eroded as compared to any known gas-evolving insulating material. The low amount of gas generated permits reliable and successful operation.

Referring to the fuse 70 illustrated in Fig. 4 of the drawing, it comprises the strain wire 72 and a fusible wire 74, both being connected to an upper terminal 76 connectible to one portion of a circuit and a lower terminal 78 connected by a flexible conductor 82 to a lower terminal 84 connectible to the other portion of the circuit. The tube 80 surrounding the wires 72 and 74 is prepared from polytetrafluoroethylene as described herein. Upon a sufficiently high current passing through the wires 72 and 74, they will fuse, thereby creating an arc. The lower contact 78 will drop either by the presence of the gases developed by the heat of the arc alone, or by a spring (not shown) operating thereon to draw out the arc further. The polytetrafluoroethylene in the tube 80 will evolve an arc-extinguishing gas thereby enabling the extinction of the arc. While an adequate quantity of arc-extinguishing gas will be evolved from the polytetrafluoroethylene, the amount of erosion of the fuse walls will not be excessive and the fuse can be reused.

The various circuit interrupting structures shown in Figs. 1 to 4 are only exemplary and not exhaustive of the types of circuit interrupting structures to which the invention may be applied. In all these arc interrupting devices, polytetra-

fluoroethylene may be employed as the arc confining and arc-extinguishing structure disposed along the path of the arc for the purpose of providing an arc-extinguishing gas. It is well known that, particularly for heavy current interrupters, the amount of arc-extinguishing gas given off may be so great that the function of the apparatus is not satisfactory. For example, the plates 24 (Fig. 1) and 42 (Fig. 2) may develop so much gas if an organic material other than polytetrafluoroethylene be employed that the arc may be driven out of the splitters by a blow back gas blast, thereby reducing the effectiveness and maximum current capacity of the interrupter. The outstanding advantage of polytetrafluoroethylene resides in the totally unexpected reduction in erosion of the material by the heat of the arc.

Referring to Fig. 5 of the drawings, there is illustrated a graph comparing the relative erosion of hard fiber and polytetrafluoroethylene in a fuse structure. It will be noted that the amount of polytetrafluoroethylene eroded is less than 20% of the volume eroded of hard fiber at a current of 1200 amperes. This enables a fuse composed of polytetrafluoroethylene to be employed many times longer before it must be discarded as compared to a fiber fuse tube. Tests made with a gas blast circuit interrupter are illustrated in the graph of Fig. 6, wherein fiber and polytetrafluoroethylene splitters are compared in volume erosion. It will be apparent that at all times the erosion of polytetrafluoroethylene is less than half of the amount of fiber eroded under the same conditions of current. This characteristic of polytetrafluoroethylene renders it highly superior for use when exposed to arcing under all conditions.

Furthermore, polytetrafluoroethylene does not carbonize appreciably as compared to any other organic material known. Tracking and creepage is much less than with other organic materials used for this purpose. This is ascribed to the fact that it does not tend to break down between the fluorine and carbon atoms but rather to depolymerize into fluorocarbon compounds which are good insulators. No evidence of free fluorine formation has been found.

Since certain changes may be made in the above description and different embodiments of the invention can be made without departing from the scope thereof, it is intended that all matter contained in the above description or shown in the accompanying drawing shall be interpreted as illustrative and not in a limiting sense.

We claim as our invention:

1. An electric circuit interrupter comprising in combination, conductor means between which an arc is formed on interruption of the circuit, and arc confining and extinguishing means disposed along the path of the arc from which an arc extinguishing medium can be evolved due to the heat of the arc for extinguishing the arc, the arc confining and extinguishing means comprising polytetrafluoroethylene.

2. An electric circuit interrupter comprising, in combination, a pair of contact members disposed to produce an arc upon separation to in-

terrupt the circuit, a chamber within which the contact members are arranged, and arc confining and extinguishing means within the chamber arranged to evolve an arc extinguishing gas due to the heat of the arc, to enable extinction of the same, the arc confining and extinguishing means comprising polytetrafluoroethylene.

3. An electric circuit interrupter comprising, in combination, a pair of contact members disposed to produce an arc upon separation to interrupt the circuit, a chamber within which the contact members are arranged, arc confining and extinguishing means comprising spaced members at one end of the chamber, and means for causing an arc to impinge on the spaced members and to pass into the spaces therebetween to evolve an arc extinguishing gas, the spaced members comprising polytetrafluoroethylene.

4. An electric circuit interrupter comprising, in combination, a pair of contact members disposed to produce an arc upon separation to interrupt the circuit, a chamber within which the contact members are arranged, arc confining and extinguishing means comprising spaced members at one end of the chamber, and means for directing a gas blast against the arc to cause it to impinge on the spaced members and to pass into the spaces therebetween to evolve an arc extinguishing gas, the spaced members comprising polytetrafluoroethylene.

5. An electric circuit interrupter comprising, in combination, a pair of contact members disposed to produce an arc upon separation to interrupt the circuit, a chamber within which the contact members are arranged, arc confining and extinguishing means comprising spaced members at one end of the chamber, a magnetic member associated with the contact members to create a magnetic field during arcing to cause the arc to impinge on the spaced members and to pass into the spaces therebetween to evolve an arc extinguishing gas, the spaced members comprising polytetrafluoroethylene.

6. In a fuse device, in combination, means adapted to fuse and form an arc on the occurrence of an overload in an electrical circuit embodying the fuse device, an arc confining and extinguishing structure associated with said means along the path of the arc from which an arc extinguishing medium can be evolved due to the heat of the arc for extinguishing it, the structure comprising polytetrafluoroethylene.
